A Split Type sight for a gun of our design includes three components. Reproductions **1.1** to **1.7** are six orthographic projection views and a perspective view of a split type sight for gun illustrating a first component in a use configuration with a second component; reproductions **1.8** to **1.14** are six orthographic projection views and a perspective view of the first component isolated for clarity, and reproductions **1.15** and **1.16** are two additional perspective views showing a variation state of the first component; reproductions **1.17** to **1.23** are six orthographic projection views and a perspective view of the second component thereof; reproductions **1.24** to **1.30** are six orthographic projection views and a perspective view of a third component thereof, and reproduction **1.31** illustrates the first component in a use configuration with the third component.

The broken lines in the reproductions depict portions of the split type sight for gun that form no part of the claimed design.
